CLAIM

The ornamental design for a faucet cartridge, as shown and described.

DESCRIPTION

FIG. 1 is a perspective view of a faucet cartridge of the new design;

FIG. 2 is a front elevational view of the faucet cartridge of FIG. 1;

FIG. 3 is a rear elevational view of the faucet cartridge of FIG. 1;

FIG. 4 is a left side elevational view of the faucet cartridge of FIG. 1;

FIG. 5 is a right side elevational view of the faucet cartridge of FIG. 1;

FIG. 6 is a top plan view of the faucet cartridge of FIG. 1; and, FIG. 7 is a bottom plan view of the faucet cartridge of FIG. 1. The broken lines shown in the figures are included for the purpose of illustrating portions of the faucet cartridge and form no part of the claimed design.

1 Claim, 4 Drawing Sheets
